(57) **CLAIM**

I claim the ornamental design for a beer dispenser, as shown and described.

DESCRIPTION

FIG. 1 is a front left perspective view of a first embodiment of a beer dispenser showing my new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is a bottom view of the design shown in FIG. 1 in an alternative state;

FIG. 9 is a front left perspective view of a second embodiment of a beer dispenser showing my new design;

FIG. 10 is a front view of the design shown in FIG. 9;

FIG. 11 is a rear view of the design shown in FIG. 9;

FIG. 12 is a left side view of the design shown in FIG. 9;

FIG. 13 is a right side view of the design shown in FIG. 9;

FIG. 14 is a top view of the design shown in FIG. 9;

FIG. 15 is a bottom view of the design shown in FIG. 9; and, FIG. 16 is a bottom view of the design shown in FIG. 9 in an alternative state.

The portions of the beer dispenser shown in broken lines are included for the purpose of illustrating environment and form no part of the claimed design.

1 Claim, 16 Drawing Sheets
